UNITED STATES PATENT OFFICE.

BENJAMIN F. LEAVITT, OF TOLEDO, OHIO, ASSIGNOR TO THE LEAVITT DIVING ARMOR COMPANY, OF TOLEDO, OHIO, A CORPORATION OF OHIO.

DIVING APPARATUS.

1,327,679.

Specification of Letters Patent. Patented Jan. 13, 1920.

Application filed January 15, 1917. Serial No. 142,438

To all whom it may concern:

Be it known that I, BENJAMIN F. LEAVITT, a citizen of the United States of America, residing at Toledo, in the county of Lucas and State of Ohio, have invented certain new and useful Improvements in Diving Apparatus, of which the following is a specification, reference being had therein to the accompanying drawings.

10 The invention relates to improvements in diving apparatus and its object is to provide a diving armor designed to permit a diver to descend to depths where the hydrostatic pressure is comparatively great, and 15 which will allow sufficient use and freedom of motion of the limbs, hands and feet to permit working at such depths.

Other objects are to facilitate the assembling and taking apart of the sections comprising the armor; to efficiently protect the electrical connections; to render the supporting cable and electrical connections quick-detachable from the armor; and to provide a safe air supply system that will 25 eliminate hose connections to the surface.

In the drawings:

Figure 1 is a front view of the armor;

Fig. 2 is a view of the same in side elevation;

30 Fig. 3 is a view partly in section showing the swivel connection of a shoulder section to the breast portion, the section being taken on line 3—3 of Fig. 2;

Fig. 4 is a fragmentary view of a clamping connection between the breast portion and a ball bearing ring.

Fig. 5 is a section on line 5—5 of Fig. 4;

Fig. 6 is a section on line 6—6 of Fig. 2, showing a detail of the connection between 40 the breast portion and said ring;

Fig. 7 is a detail sectional view of the free extremity of one of the arm sections, the section being taken on line 7—7 of Fig. 1;

Fig. 8 shows in detail the construction of 45 the hollow supporting cable with conductors passing through the same;

Fig. 9 is a detail sectional view of the connection between the helmet and the electrical conductors.

50 In these views A, B and C respectively denote a body section, a section comprising a helmet and breast portion, and a shoulder section, said sections being rigid, metallic and pressure-resisting; and D and E designate respectively flexible arm and leg sec-

tions, the latter of which carry rigid metallic feet F. The corresponding arm and shoulder sections preferably form a permanently connected detachable unit carrying a swivel member, presently to be described, rigidly 60 engageable with the breast portion. In order to give high resistance against pressure and still secure flexibility, tubular metallic coils 1 are employed for the limb sections, the adjacent convolutions thereof 65 being interlocked, as is best seen in Fig. 7. To render these coils water-proof they are coated exteriorly with a thick layer of rubber 2. As the high water pressure, encountered in deep-sea diving, will have a 70 tendency to force this rubber between the convolutions of the coils it is preferred to interpose a layer 3 of heavy canvas or thin flexible metal between the metallic coils and the water-proofing coating. The preferred 75 manner of applying the coating is to first wind on the canvas or thin metal in strips, then cover the same with a layer of rubber of the proper thickness and finally vulcanize in position. At moderate depths it 80 is practicable to employ the metallic coils for the limb sections omitting the rubber coating, but when the armor is to be used at considerable depths, as for example 300 feet, the additional water-proofing, as described, is essential.

It is preferred to form the helmet and breast portion of the armor as a detachable unit, and to provide in the breast portion, orifices 4 through which the arms may be 90 passed. Between the abutting edges of the breast portion and body section, there is interposed a packing ring 4^a, said edges being formed with annular grooves to receive said ring.

95 To facilitate and expedite the clamping upon the body section of the section comprising the helmet and breast portion and the taking apart of said sections, a cam mechanism is employed which will now be described. A ring 5 encircles the upper end of the body section and is formed with a plurality of circumferential grooves 6 each of which receives a roller 7 mounted upon a stud bolt 8 rigidly carried by the body section. Said rollers support the ring 5 and coact with the grooves 6 to limit its rotation. From the upper edge of said ring a plurality of lugs 10 project upwardly, the end portions of said lugs being bent in a substan-

tially horizontal direction and being formed with similarly inclined cam faces 10^a which are engageable respectively with studs 11 rigidly projecting from the breast portion. 5 Thus, when the cam ring is subjected to a slight rotation upon the body section the inclined faces of the members 10 will ride along the studs 11 and the two abutting sections may thereby be firmly drawn together 10 and held rigidly engaged. As a means for applying leverage to the cam ring 5 to turn the same, said ring is formed with a groove 12 having one of its circumferential edges formed by a rack of teeth engaged by a pinion 13 mounted in said groove and rotatively 15 carried by the body section, said pinion being formed with a polygonal stud 14 with which a wrench may be engaged to rotate the pinion. Thus it is seen that when the section 20 comprising the breast and helmet portions has been placed upon the body section with the studs 11 adjacent to the lugs 10, a slight rotation applied to the pinion 13 will suffice to firmly interengage the members 10 25 and 11 and clamp the packing 4^a between the two sections.

The joint between the breast portion and shoulder section will now be described. (See Fig. 3). Each shoulder section is formed 30 with an annular flange 15 which is adapted to fit within one end of a ring 16 formed at its other end with an inwardly projecting flange 17. The flange 17 forms a seat for a ball bearing 18, said bearing being interposed between the flanges 17 and 15. The 35 ring 16 forms a retainer for the ball bearing and is held swivelly engaged with the shoulder section by an annular nut 19 which overhangs the flange 15 and is screwed into said ring. To permit said nut to be tightened without clamping the ball bearing, a shoulder 19^a is provided upon the ring as a seat for the nut. Besides retaining the shoulder 15 in swivel engagement with the 40 ring 16, the nut 19 also compresses the packing 20 between said ring and the flange 15. An outwardly projecting annular flange 21 carried by the ring 16 is in juxtaposition to a flange 21^a upon the breast portion and a 45 packing ring 22 is adapted to be clamped between the two said flanges. To create the clamping stress there is rigidly mounted upon the flange 21^a a plurality of spaced studs 24 having heads 24^a, the bottom faces 50 of which are beveled at a slight angle to the plane faces of said flange. (See Figs. 4 and 5.) The flange 21 is formed with corresponding circumferential slots 25, of a width substantially equal to the thickness of the 55 shanks of said studs and each of said slots 60 communicates at one end with an orifice 25^a proportioned to allow one of the stud heads to pass therethrough. Upon the outer face of the flange 21, there is formed a series of 65 U-shaped projections 26, the slots 25 being

formed between the legs of these projections, the outer faces of said projections having a bevel corresponding to that of the heads of the studs. Thus it is seen that an arm and shoulder unit may be quickly clamped to the 70 breast portion by registering the orifices 25^a with the heads 24^a of the studs, then displacing the arm and shoulder unit to engage the flange 21 with the flange 21^a of the breast portion and finally rotating the 75 flanged ring sufficiently to interengage the inclined faces of the stud heads 24^a and projections 26. To secure a leverage for forcibly applying a limited rotation to the ring 16, each flange 21 is formed with an arcuate 80 rack 27 with which is engaged a pinion 28 mounted rotatively on a lug 28^a, peripherally formed upon the flange 21^a, each of said pinions being provided with a polygonal stud 28^b to which a wrench may be applied 85 to rotate the pinion. It is to be noted that the axes of rotation of the two arm sections are not alined, but intersect at a slight rearward inclination. Thus the arms do not rotate in parallel planes but approach each 90 other at their free ends as they are raised to a horizontal position.

An appliance carried by the free ends of the arm sections to permit use of the hands will now be described. (See Fig. 7.) A 95 ring 29 is clamped rigidly upon the free end of each arm section and is formed with an inwardly projecting annular flange 29^a against which the extremity of said section abuts. Below this flange and within said 100 ring there is disposed a ball bearing 30, upon which bearing is adapted to turn a circular plate 31 formed with an annular flange 32 to engage said bearing. A ring nut 33 retains the member 31 and the ball 105 bearing within the ring 29, said nut being seated against a shoulder 34 in said ring and retaining packing 34^a in place between the members 31 and 29. A downwardly projecting portion 35 of the plate 31 constitutes a bearing for a pair of alined rock 110 shafts 36, the inner ends of which project into a recess 37 extending into the member 31. Between the inner ends of said rock shafts there is placed a ball 37^a which serves 115 to reduce the friction resulting from the end thrust to which said rock shafts are subjected by hydrostatic pressure. Said rock shafts project exteriorly from the bearing 35 and respectively rigidly carry the 120 shanks 40 of a pair of gripping members 41, said shanks including portions 42 projecting toward each other to dispose the gripping members in proximity. The gripping members are slightly hooked so that they may 125 coact to hold an interposed object. Within the recess 37, handles 43 are respectively rigidly mounted upon the rock shafts 36, said handles being extended upwardly and being provided with grips 44 to be engaged 130

by a hand of the diver. The end portions of the bearing 35 form stuffing boxes for the rock shafts in which stuffing boxes packing 47 is compressed by packing glands 48. 5 From the foregoing description it will be seen that the diver by drawing the handles 43 together can engage an object between the gripping members and furthermore by means of said handles the gripping members 10 may be rotated through any desired arc for convenience in gripping the object. It has been found that at considerable depths the hydrostatic pressure exerted end-wise of the limb sections tends to collapse 15 the convolutions of said sections one upon the other so as to deprive these sections of flexibility. To counteract this tendency there is associated with each arm section a pair of swinging struts 50 respectively at 20 the front and back thereof, the upper extremities of these struts being pivoted upon studs 51 carried by the shoulder sections and their lower extremities engaging studs 52 carried by the ring 29. Similarly there is 25 associated with each leg section a pair of swinging struts 53 one at each side thereof, the upper and lower extremities of which pivotally engage studs 54 and 55, the former carried by the body section and the latter 30 by a ring 55^a clamped upon the lower end of the leg section. The struts 50 and 53 prevent collapse of the metal coils 1 but do not prohibit flexing of said coils, since they will accommodate themselves to the bending 35 of the limb sections by swinging around their pivots.

Since the swivel mounting of the foot sections F is the same as that of the members 41 at the ends of the arm sections, no description thereof need be given.

The supporting cable which is employed to raise and lower the diver is indicated at 40 56 and is preferably made hollow to receive electrical conductors 57 which establish telephone connection to the surface and supply current for lighting if desired. The cable proper will preferably be formed of woven wire, and has an interior lining formed of a metallic coil 57^a preferably having interlocked convolutions such as employed on a 45 larger scale in the limb sections. This lining serves to prevent abrasion of the insulation of the conductors, which would otherwise result from the relative motion of 50 the cables and conductors resulting from flexing. For engagement with the helmet the cable 56 is looped, as indicated at 58, and the loop is engaged with a pair of sister hooks 59 pivoted to the top 55 of the helmet. This permits the cable to be readily detached from the armor when desired, since the loop 58 may be freed from said hooks by swinging the latter apart to each side thereof, as indicated in 60 Fig. 1.

The means employed for producing a water-tight joint at the point of entry of the electric connections into the helmet will now be described. A nut 60 is engaged in an orifice of the helmet and is exteriorly 70 flanged, as indicated at 61. Against the outer end of said nut 60, there bears a nut 62, a packing ring 63 being interposed between the members 60 and 62. Said members are clamped firmly together by a lock 75 nut 64 having threaded engagement with the nut 62 and having a flange 64^a engaging the flange 61. The packing nut 62 is further engaged by one end of a clamping nut 65, the other end of which is formed with a 80 flared orifice engaging a tapered collar 66 fastened upon the cable extremity, this engagement tending to draw the cable toward the helmet when said nut is tightened and thereby clamp a packing ring 66^a between 85 said collar and the nut 62. These connections eliminate any possibility of leakage at the point of entry of the electrical conductors into the helmet, said conductors being extended through central orifices of the 90 nuts 60 and 62 and being detachably engaged within the helmet with a plug 68 with which the conductors of the armor are permanently connected.

The usual system of supplying air to 95 divers, namely pumping the same from the surface becomes impracticable when working at extraordinary depths and in place of this usual system, the invention provides an oxygen supply to be carried by the diver together with means for absorbing the carbonic acid gas and moisture from the gases given off from the lungs. This system comprises primarily an oxygen tank 68^a and caustic soda tank 69, the latter tank being 100 provided with an intake 70 at its lower end and having at its top an outlet communicating with a pipe 71 extending to the mixing chamber 72. The oxygen tank is also provided with an outlet pipe 73 controlled by 105 a valve 74 and communicating with said mixing chamber. From the chamber 72 a pipe 75 extends upwardly and discharges in the front portion of the helmet. In the operation of this system, the gases from the 110 lungs of the diver are diffused throughout the armor and eventually enter the intake 70 of the tank 69. In passing through said tank, the carbonic acid gas and moisture are absorbed by the caustic soda and the nitrogen is conducted to the mixing chamber 72 where it encounters a predetermined amount of oxygen from the tank 68^a, the valve 74 being so regulated that the mixture of oxygen and nitrogen formed in the chamber 72 115 will have substantially the proportions of pure air. This mixture rising in the pipe 75 is drawn into the lungs of the diver where the amount of oxygen necessary to maintain vitality is withdrawn.

With the system so far described there is danger of water having access to the caustic soda in case of leakage, and to safeguard against such a contingency a spring-pressed valve 76 is associated with the inlet valve of the caustic soda tank and is normally maintained in open position by a soluble solid body 77 interposed between a nut 78 upon the valve stem and a bearing 79 supporting said stem. As soon as water rises within the armor to the level of the inlet of the tank 69 the body 77 is dissolved, thereby permitting the valve 76 to close.

What I claim as my invention is:

- 15 1. In a diving apparatus, the combination with an arm section, of a member swivelly carried by said section at the free end thereof and constituting a closure for the section, a pair of rock shafts carried by said member, gripping members respectively carried by said rock shafts exteriorly to the arm section, and handles carried by said rock shafts within the arm section.
- 20 2. In a diving apparatus, the combination with a diving armor including a helmet section, a tank for receiving an absorbent chemical, a pipe communicating with the last-mentioned tank discharging in the helmet section, means for replenishing the oxygen consumed by the diver, a closure for an inlet in the bottom of the chemical tank, and means for automatically closing said inlet upon a rise of water within the armor to a predetermined level.
- 25 3. In a diving apparatus, the combination with two adjacent rigid metallic sections, of a ring carried by one of said sections and rotatable thereupon, of means establishing a cam engagement between said sections through said ring, and means furnishing leverage for establishing said cam engagement.
- 30 4. In a diving apparatus, the combination with a diving armor, of a tank for receiving an absorbent chemical, said tank

having an inlet and an outlet in communication with said armor, means for replenishing the oxygen consumed by the diver, a closure for the inlet of the chemical tank, and means for automatically seating said closure upon a rise of water within the armor to a predetermined level.

5. In a diving apparatus, the combination with a diving armor, of a tank for receiving an absorbent chemical having an inlet and an outlet in communication with said armor, means for replenishing the oxygen consumed by the diver, a closure for the inlet of said tank, means acting on said closure tending to seat the same, and a soluble body opposing the last-named means whereby said closure will seat upon a rise of water within the armor to the level of said soluble body.

6. In a diving apparatus, the combination with a diving armor, of a tank carried by said armor and in communication therewith for receiving a caustic for absorbing moisture or carbonic acid gas generated within the armor, and means for automatically closing communication between said tank and armor upon a rise of water within the armor to a predetermined level.

7. In a diving apparatus, the combination with a diving armor, of a tank for receiving an absorbent chemical carried by said armor and having communication therewith, means for replenishing the oxygen consumed by the diver, a closure for cutting off communication between the armor and said tank, a stem for said closure, a guide for said stem, a spring acting upon the closure tending to seat the same, and a soluble body interpose between said guide, and a shoulder on said stem opposing said spring whereby a rise of water within the armor to the level of said soluble body will automatically seat said closure.

In testimony whereof I affix my signature,
BENJAMIN F. LEAVITT.
